CLAIM

The ornamental design for a paint brush and handle, as shown and described.

DESCRIPTION

FIG. 1 is a top view of the paint brush and handle with the bottom view being a mirror image thereof;

FIG. 2 is a left side view of the paint brush and handle with the right side view being a mirror image thereof;

FIG. 3 is a front view of the paint brush and handle; and,

FIG. 4 is a rear view of the paint brush and handle.
The broken lines shown in the drawings form no part of the claimed design.
